(57) **CLAIM**

The ornamental design for a liquid-cooled energy storage outdoor cabinet as shown and described.

DESCRIPTION

FIG. 1 is a front view of a liquid-cooled energy storage outdoor cabinet in accordance with the present application; FIG. 2 is a rear view thereof; FIG. 3 is a left view thereof; FIG. 4 is a right view thereof; FIG. 5 is a top view thereof; FIG. 6 is a bottom view thereof; FIG. 7 is one perspective view thereof; and, FIG. 8 is another perspective view thereof. The broken lines in the drawings depict portions of the liquid-cooled energy storage outdoor cabinet that form no part of the claimed design.
